UNITED STATES PATENT OFFICE

96,267

DESIGN FOR A BOTTLE

Albert C. Meyer, Glenshaw, Pa., assignor to The Glenshaw Glass Company, Glenshaw, Pa., a corporation of Pennsylvania

Application May 24, 1935, Serial No. 56,989

Term of patent 7 years

To all whom it may concern:

Be it known that I, Albert C. Meyer, a citizen of the United States, residing at Glenshaw, in the county of Allegheny and State of Pennsylvania, have invented a new, original, and ornamental Design for Bottle, of which the following is a specification, reference being had to the accompanying drawing, forming part thereof.

side elevational view of the bottle showing my new design.

The rear elevation (not shown) is substantially the same as Figure 1.

I claim:

The ornamental design for a bottle as shown and described.

ALBERT C. MEYER.
